Primary Examiner—Robin V Webster
(74) Attorney, Agent, or Firm—Harness, Dickey & Pierce, P.L.C.(57) **CLAIM**

The ornamental design for a deflector for a fire protection sprinkler, as shown and described.

DESCRIPTION

FIG. 1 is a perspective view of a deflector for a fire protection sprinkler;

FIG. 2 is a bottom view thereof (the top view is identical to the bottom view);

FIG. 3 is a front side view thereof;

FIG. 4 is a right side view thereof; and,

FIG. 5 is a right side view (the left side view is identical to the right side view).

The broken line showing is included for the purpose of illustrating and forms no part of the claimed design.
